CIRCUIT BREAKER

Merrill G. Leonard, Sharon, Pa., assignor to
Westinghouse Electric & Manufacturing Com-
pany, East Pittsburgh, Pa., a corporation of
Pennsylvania

Application September 19, 1940, Serial No. 357,391

12 Claims. (Cl. 200—116)

The invention relates to circuit interrupters and more particularly to multipole circuit breakers of the type which are manually operable and also automatically operable in response to predetermined abnormal conditions.

The present invention in certain respects constitutes a further development and improvement of the circuit breaker disclosed in my copending application Serial No. 163,202, filed September 10, 1937, assigned to the assignee of this invention, and now Patent No. 2,227,506, issued January 7, 1941.

An object of the present invention is the provision of an improved multipole circuit breaker that is simple, compact, and inexpensive to manufacture.

Another object of the invention is the provision of a multipole circuit breaker embodying an individual actuating mechanism and trip means for the contacts of each pole, with means which utilize the energy released during or after tripping of any one pole to automatically trip the other poles.

Another object of the invention is the provision of an improved multipole circuit breaker having an individual actuating means and trip means for the contacts of each pole, and a novel interlocking means operable when any pole of the breaker trips to automatically effect tripping of the other poles.

Another object of the invention is the provision of a multipole circuit breaker having an individual actuating means and trip means for the contacts of each pole, and an interlock which utilizes the kinetic energy of the moving contact arm of whichever pole is tripped at the end of its opening motion to automatically trip the other pole or poles.

Another object of the invention is the provision of an improved multipole circuit breaker mechanism in which the opening movement of the contact arm of any pole upon tripping thereof is utilized to move the electroresponsive trip element of the other pole to automatically trip the other pole.

Another object of the invention is the provision of a circuit breaker with a novel self-aligning contact means of simple and inexpensive construction.

The novel features that are considered characteristic of the invention are set forth in particular in the appended claims. The invention itself, however, both as to construction and operation, together with additional objects and advantages thereof, will be best understood from the following detailed description of one embodiment thereof when read in conjunction with the accompanying drawings, in which:

Figure 1 is a vertical sectional view taken through one of the poles of the circuit breaker,

the parts being shown in the closed circuit position;

Fig. 2 is a front elevational view of the circuit breaker;

5 Fig. 3 is a fragmentary perspective view of the circuit breaker mechanism;

Fig. 4 is an enlarged view, partly in section, of the contact means and switch arm of the breaker; and

10 Fig. 5 is a sectional view similar to Fig. 1 showing the position of the parts when one pole of the breaker has been tripped.

Referring to the drawings, the circuit breaker illustrated is of the two-pole type and includes a housing 9 of molded insulating material which serves to support and enclose the various parts of the circuit breaker mechanism. The housing is divided into two compartments by a longitudinal partition formed integral with the housing to provide chambers for the mechanisms of the two poles of the breaker. The two poles of the circuit breaker are substantially identical in construction, and hence a detailed description of only one pole will be given, since it is believed that it will be sufficient for a clear understanding of the invention.

15 Each pole of the circuit breaker comprises in general a stationary contact 11, a cooperating movable contact 13 carried by a movable switch arm 15, actuating means indicated generally at 17 for moving the switch arm to open and closed circuit position, and a trip device indicated generally at 19 which is operable in response to predetermined current conditions in the circuit of 20 its pole to cause the actuating means to automatically open the contacts.

25 The stationary contact 11 is secured to the inner angularly bent end of a terminal conducting strip 21, which is secured to the end 30 wall of the housing by suitable rivet fastening means 23. The opposite end of the terminal conducting strip 21 is angularly bent, and extends outside of the housing 9 for connecting the breaker to an external electrical circuit.

35 The movable contact 13 is carried by the switch arm 15 which is generally U-shaped, as best shown in Fig. 3. The switch arm 15 is stamped from sheet metal, and is bent to provide a pair of parallel legs 25 (Fig. 3) and a bight portion 40 27.

45 The movable contact 13 is mounted on a projection 29 which is formed integral with the switch arm 15. The bight portion 27 of the switch arm 15 is provided with an extension 31 which has a pair of lugs 33 extending laterally 50 from the sides thereof and formed integral therewith for a purpose which will be hereinafter described.

55 The actuating means for the movable contact 13 comprises in general a pivoted releasable member 35 to which the switch arm 15 is pivoted, a

movable operating member 37, and an overcenter spring 39 connecting the operating member and the bight portion 27 of the switch arm 15.

The pivoted releasable member 35 is stamped from sheet metal plate and formed to provide a pair of spaced parallel legs 41 (Fig. 3) which are joined by a bridge portion 45 at the inner end. The releasable member 35 is pivotally supported by means of a pivot pin 47, the ends of which are removably engaged in suitable bearing recesses 49 (Fig. 1) formed in the insulating material of the housing. The switch arm 15 is nested within the legs 41 of the releasable member 35, and is pivoted to the releasable member by a pair of short pivot pins 53. It will thus be seen that the releasable member 35 and the switch arm 15 connected thereto are removably mounted in the housing 9, and these elements are adapted to be retained in mounted position by means of the overcenter spring 39.

The operating member 37 is also stamped from sheet metal plate and formed to provide a pair of outstanding legs 55 (Fig. 2), which are provided with openings for engaging a common operating member which will be hereinafter described. The operating member 37 is provided at each end with a pair of lateral projections 59 (Fig. 2) which are adapted to slide on spaced parallel arcuate surfaces 61 formed on the molded housing. Suitable ribs 62 (Fig. 2) are provided on the housing adjacent the arcuate guide surfaces 61 for guiding the operating member 37 and preventing lateral displacement thereof. The operating member 37 and the bight portion 27 of the switch arm 15 are perforated to receive the hook ends of the overcenter spring 39. The overcenter spring 39 is held in tension between the switch arm 15 and the operating member 37, and thus serves to maintain the pivoted releasable member 35 and the operating member 37 in mounted position in the molded housing.

The spring 39 is disposed between the legs of the switch arm 15 and the legs of the pivoted releasable member 35, and in the closed circuit position of the breaker the line of action of the spring 39 is so disposed relative to the pivot axis 47 of the releasable member 35 that it tends to bias the releasable member in an upward or clockwise direction about the pivot axis 47. The releasable member 35 is normally held in the latched position shown in Fig. 1 by means of the current-responsive trip device 19, the bridging portion 45 of the releasable member 35 being provided with a latch projection 63 which normally engages a latch 65 carried by the trip device.

The downward movement of the operating member 37 is limited by a pair of stops 66 (Fig. 2) adjacent the arcuate surfaces 61. The stops 66 are adapted to be engaged by the upper lateral projections 59 of the operating member 37 in the closed circuit position of the operating member, as shown in Fig. 2. Upward movement of the operating member 37 is limited by the engagement of the lower lateral projections 59 of the operating member with a pair of projections 67 formed on the legs 41 of the pivoted releasable member 35. The projections 67 extend through the opening in the housing between the sides of the operating member 37 and the arcuate surfaces 61 as best shown in Fig. 2.

The projections 67 of the releasable member 35 and the lower lateral projections 59 of the operating member 37 form a means for resetting

the releasable member 35 to its latched position when the operating member is manually moved upwardly beyond its normal open position following a tripping operation.

5 The trip device 19 comprises a U-shaped bimetallic trip element 69 which has its bight portion 71 (Fig. 3) secured to a pivoted adjusting arm 73 by means of a plurality of rivets 75. The lower ends of the legs of the trip element 69 10 have an insulating block 77 secured thereto by rivets 79. The latch 65 is secured to the lower end of the block 77 by means of a pair of rivets 81.

The pivoted adjusting arm 73 is provided with 15 a pair of ears 83 bent at right angles to the adjusting arm 73, and the ears 83 are provided with aligned openings for engaging a pivot pin 85 which is supported in bearings provided therefor in the molded housing 9. The bimetal trip element 69 and its adjusting arm 73 are thus pivotedly mounted in the housing 9, and it will be seen that rotative movement of the adjusting arm 73 about the pivot 85 will change the position of the latch 65 with respect to the latch projection 63 of the pivoted releasable member 35.

30 The right-hand end of the adjusting arm 73 is notched to receive an adjusting screw 89 which passes through a transverse partition wall 91 formed in the housing 9. The screw 89 is held in mounted position on the partition wall 91 by means of a nut 93. A tubular adjusting nut 95 is threaded on the end of the screw 89, and this nut engages the notched end of the adjusting arm 73. The tubular nut 95 is provided with a knurled portion 97 which extends through an opening 96 provided therefor in the upper end wall 99 of the housing to provide for manual adjustment of the nut 95.

40 A coil compression spring 103 encircles the screw 89 and engages the notched end of the adjusting arm 73 at one end and the transverse partition wall 91 at its other end. The spring 103 serves to maintain the notched end of the 45 adjusting arm 73 in engagement with the tubular adjusting nut 95.

45 From the foregoing description of the trip device, it will be apparent that when the nut 95 is screwed down it will move the adjusting arm 73 and bimetal trip element 69 in a clockwise direction about the pivot 85, and thereby decrease the amount of overlap between the latch 65 carried by the bimetal trip element 69 and the latch projection 63 of the releasable member 35. This 55 will cause the breaker to be tripped in response to a lower magnitude overload. Conversely, when the nut 95 is screwed out, that is, backed off, the amount of overlap between the latch 65 and the latch projection 63 is thereby increased, so that a higher value of overload current is required to effect tripping of the breaker.

55 As has previously been mentioned, the structures of the two poles of the breaker are identical, and are insulated from one another by a centrally disposed longitudinal partition wall 110 formed in the housing 9. The operating members 37 for the two poles are connected for simultaneous movement together by a common operating member 111 of insulating material. The common operating member 111 is in the form of a yoke, and the opposite arms thereof extend through the openings provided therefor in the two operating members 37. An operating rod (not shown) is adapted 70 to be connected to the central portion of the common operating member 111.

A cover 117 of molded insulating material is removably secured to the housing 9 for the purpose of enclosing and protecting the current-responsive trip devices 19. The cover 117 is provided with a central longitudinal partition 119 which aligns with the partition 110 formed in the housing 9 so as to completely isolate the two poles of the breaker from one another.

The circuit for each pole of the breaker is the same and extends from the lower terminal strip 10 21 through the stationary contact 11, the movable contact 13, and a flexible shunt conductor 123 connected to the movable contact, to one leg of the bimetal trip element 69, and through 15 the bimetal trip element 69 and a flexible shunt conductor 125 to an upper terminal strip 127 (Fig. 2), the end of which extends outside of the casing on the side thereof.

Referring to Fig. 4, the movable contact 13 is mounted on the switch arm 15 for limited tilting or swiveling movement relative thereto, so as to permit the contact to seat flat against the stationary contact 11. For this purpose, the movable contact 13 is provided with a reduced cylindrical portion 129 between the front and back 25 thereof, and is formed to provide substantially spherical shoulders 131 adjoining the reduced portion. The movable contact is loosely retained in a C-shaped notch 133 provided therefor in the lower projection 29 of the switch arm 15. The extending fingers 135 forming the notch are bent toward each other slightly to retain the contact 13 in the notch. The fingers, however, are not bent far enough to bind the contact. The flexible shunt conductor 123, which connects the movable contact to one end of the bimetal trip element 69, is rigidly attached at its other end to the back of the movable contact 13, and extends through and is firmly held in a bushing 137 which is mounted in a notch provided in the bight portion 27 of the switch arm 15.

The spherical shoulders 131 permit the movable contact 13 to tilt or swivel a slight amount, so as to seat flat against the stationary contact 11 when it is moved to closed circuit position.

The circuit breaker is provided with an interlock mechanism designed so that when either pole of the breaker trips the other pole will also trip. The interlock mechanism utilizes the kinetic energy of either of the switch arms 15 as it approaches the tripped open position to effect release of the latch on the other pole to thereby trip the other pole of the circuit breaker.

The interlock mechanism comprises a bar 139 of insulating material which is transversely disposed in the upper portion of the housing 9 between the partition wall 91 and the upper end wall 99 of the housing. The bar 139 is pivotally mounted intermediate its ends on a rod 141 which is mounted in the housing 9. The rod 141 has its inner end engaged in a bearing provided therefor in the mid portion of the bar 139, and the other end is bent upwardly at a right angle and extends through a notch 143 (Fig. 2) provided therefor in the upper end wall 99 of the housing. The angularly bent end of the pivot rod 141 is securely retained in the notch 143 by a pair of nuts 145 which are threaded on the rod and engage the opposite sides of the end wall 99, as shown in Fig. 2.

The opposite ends of the insulating bar 139 are disposed directly above the notched ends of the adjusting arms 73 on the side thereof opposite the coil springs 103. The opposite ends 70 of the bar 139 engage the heads of a pair of pins

147 which are slidably mounted in openings provided therefor in the partition wall 91. The pins 147 extend through the notches in the ends of the adjusting arm 73, and the heads of the pins are disposed between the adjusting arm 73 and the insulating bar 139. The lower ends of the pins 147 project through the transverse partition wall 91, and are disposed to be engaged and moved by angularly bent projections 149 of the switch arms 15 as the switch arms approach the tripped open position.

When either pole of the circuit breaker is tripped in response to predetermined overload conditions, the releasable member 35 of the affected pole is released by the tripping of the latch 63, and the corresponding switch arm 15 is caused to move to a tripped open circuit position, as shown in Fig. 5. As the switch arm 15 approaches the tripped open position, the projection 149 thereof strikes the pin 147 and the impact causes the insulating bar 139 to rotate on the pivot 141, thus pushing the adjusting arm 73 of the other pole. This causes rotation of the adjusting arm 73 of the other pole about its pivot 85, moving the bimetal trip element 69 and latch 65 to release the releasable member 35 of the other pole to cause tripping thereof. When the circuit breaker is manually operated to the open-circuit position, the projections 149, as shown dotted in Fig. 1, do not engage the pins 147, and hence the interlock bar 139 is not affected by manual opening of the circuit breaker.

The operation of the circuit breaker is briefly as follows: To manually open the circuit breaker, the common operating member 111 is moved in an upward direction to effect simultaneous upward movement of the two operating members 37 which are connected thereto. The upward movement of the operating members 37 moves the line of action of the overcenter springs 39 across and above the pivot axis 53 of the switch arms 15. As soon as the line of action of the overcenter springs crosses above the pivot axis 53, the springs act to move the two switch arms 15 simultaneously to the open circuit position, indicated by the dotted lines in Fig. 1. This movement of the switch arms takes place with a snap action.

To manually close the circuit breaker, the common operating member 111 is moved downwardly to effect simultaneous downward movement of the two operating members 37. The downward movement of the operating members 37 moves the line of action of the overcenter springs 39 across and below the pivot axis 53 of the switch arms 15. As soon as the line of action of the overcenter springs 39 crosses below the pivot axis 53, the springs act to move the switch arms 15 to the closed circuit position shown in Fig. 1 with a snap action.

When an overload of predetermined magnitude and duration occurs in the circuit through either pole of the circuit breaker, the bimetal trip element 69 of the affected pole is heated thereby a sufficient amount to deflect in a direction away from the actuating means. This deflection of the trip element causes the latch 65 to disengage the latch projection 63 of the releasable member 35, effecting release of the releasable member. The overcenter spring 39 of the affected pole then moves the pivoted releasable member 35 in a clockwise direction about its pivot axis 47 from the position shown in Fig. 1 to the position shown in Fig. 5. During this movement, the legs 41 of the pivoted releasable member 35 engage the lat-

eral projections 33 of the switch arm 15 and move the switch arm to the tripped open circuit position, as shown in Fig. 5, to effect opening of the contacts.

As has previously been described, the tripping of either pole of the circuit breaker will operate through the interlock bar 139 to also effect tripping of the other pole of the breaker. As the switch arm 15 of the pole on which initial tripping occurs approaches its tripped open circuit position, the projection 149 thereof strikes the pin 147 on that pole and the impact causes rotation of the interlock bar 139 about its pivot 141. The opposite end of the bar 139 pushes the adjusting arm 73 of the trip element of the other pole inwardly, causing rotation of the adjusting arm 73 and the bimetal trip element 69 about the pivot 85 to effect release of the releasable member 35, thereby tripping the other pole of the circuit breaker.

Before the circuit breaker can be reclosed following a tripping operation, it is necessary to reset the pivoted releasable members 35 to their latched position. To reset the circuit breaker, the common operating member 111 is moved in an upward direction slightly beyond the normal open position thereof. During this movement, the lower lateral projections 59 of the operating members 37 engage the projections 67 of the pivoted releasable members 35 and effect movement of the releasable members in a counterclockwise direction about their pivot axes 47 to return the releasable members to their latched position. After the pivoted releasable members have thus been returned to latched position, the breaker may be manually closed in the manner previously described.

While the invention has been disclosed in accordance with the provisions of the patent statutes, it is to be understood that various changes in the structural details thereof may be made without departing from some of the essential features of the invention. It is desired, therefore, that the language of the appended claims be given the broadest reasonable construction permissible in the light of the prior art.

I claim as my invention:

1. A multiple circuit breaker comprising a movable contact arm for each pole, actuating means for each contact arm comprising an overcenter spring for moving the contact arm to open and to closed circuit position with a snap action and a current-responsive trip element operable to cause movement of the contact arm to open circuit position, means operable by the opening movement of the contact arm of any pole when tripped for causing movement of the current-responsive trip element of the other of the poles to trip the other of the poles.

2. A multipole circuit breaker comprising a set of separable contacts for each pole, an actuating means for the contacts of each pole including a current-responsive tripping means operable to cause automatic opening of the contacts of its pole, and means comprising an interlock bar pivoted intermediate its ends for movement in a plane at right angles to the plane of movement of the movable contacts and disposed to be moved by the opening movement of the actuating means of any pole upon tripping thereof to cause tripping of the other of the poles.

3. A multipole circuit breaker comprising a set of contacts and a movable contact arm for each pole, an actuating means for each contact arm including a member releasable to cause auto-

matic circuit opening operation of said contact arm and a pivotally mounted current-responsive trip element operable in response to predetermined current conditions in the circuit through its pole to effect release of said releasable member; and means comprising an interlock bar pivoted intermediate its ends disposed to be moved by the opening movement of the contact arm of any pole upon tripping thereof to move the trip element of the other of the poles about its pivot to effect tripping of the other of the poles.

4. A multipole circuit breaker comprising a set of separable contacts for each pole, an actuating means for each set of contacts for opening and closing the same and a pivotally mounted current-responsive bimetal trip element for each of a plurality of the poles deflectable in response to predetermined current conditions in the circuit of its pole to cause automatic opening of the contacts of its pole, a separate adjusting means for each bimetal trip element for moving the bimetal element about its pivot to adjust the trip characteristic of the corresponding pole of the breaker, and means operable by the opening movement of the actuating means of any pole when tripped to move the bimetal trip element of other of the poles about its pivot to effect tripping of other of the poles.

5. A multipole circuit breaker comprising a set of separable contacts and a movable contact arm therefor for each pole, an actuating means for each contact arm comprising an overcenter spring operable to move said contact arm to open and to closed circuit position, a member releasable to cause movement of said contact arm to open circuit position, and a current-responsive trip element for each of a plurality of the poles operable in response to predetermined current conditions in the circuit of its pole to effect release of said releasable member and thereby cause movement of the contact arm of its pole to open circuit position, manually operable means for moving said overcenter springs to manually actuate said contact arms, and means operable by the opening movement of the contact arm of any pole when tripped to cause the current responsive trip element of other of said poles to release its corresponding releasable member and thereby trip the other of said poles.

6. A multipole circuit breaker comprising a set of separable contacts and a movable contact arm therefor for each pole, an actuating means for each contact arm comprising an overcenter spring operable to move said contact arm to open and to closed circuit position, a member releasable to cause movement of said contact arm to open circuit position, and a current-responsive trip element operable in response to predetermined current conditions in the circuit of its pole to effect release of said releasable member and thereby cause movement of the contact arm of its pole to open circuit position, manually operable means for moving said overcenter springs to manually actuate said contact arms, and means comprising an interlock bar disposed to be moved by the contact arm of any pole when tripped to move the current-responsive trip element of other of the poles to trip said other of the poles.

7. A multipole circuit breaker comprising a set of separable contacts and a movable contact arm therefor for each pole, an actuating means for each contact arm comprising an overcenter spring operable to move said contact arm to open and to closed circuit position, a member releasable

able to cause movement of said contact arm to open circuit position, and a pivoted current-responsive trip element for each of a plurality of the poles operable in response to predetermined current conditions in the circuit of its pole to effect release of said releasable member and thereby cause movement of the contact arm of its pole to open circuit position, manually operable means for moving said overcenter springs to manually actuate said contact arms, and means comprising an interlock bar pivoted intermediate its ends disposed to be moved by the opening movement of the contact arm of any pole when tripped to cause release of the releasable member of other of the poles to thereby effect tripping of other of the poles.

8. A multipole circuit breaker comprising a set of separable contacts and a movable contact arm therefor for each pole, an actuating means for the contact arm of each pole comprising a releasable member pivoted on a stationary support, said contact arm being pivotally supported on said releasable member, an overcenter spring connected to the contact arm operable to move the contact arm to open and to closed circuit position while said releasable member remains stationary, said pivoted releasable member being normally restrained and being moved by said spring when released to cause automatic movement of the contact arm to open circuit position, and a current-responsive trip element operable in response to predetermined current conditions in the circuit through its pole to effect release of the releasable member of its pole, and means comprising a bar which is moved during the opening movement of the contact arm of either pole upon tripping thereof to effect tripping of the other pole.

9. A multipole circuit breaker comprising a set of separable contacts and a movable contact arm therefor for each pole, an actuating means for the contact arm of each pole comprising a pivoted releasable member to which the contact arm is pivoted, an overcenter spring connected to the contact arm operable to move the contact arm to open and to closed circuit position, said pivoted releasable member being normally restrained and being moved by the spring when released to cause automatic movement of the contact arm to open circuit position, and a pivoted current-responsive bimetal trip element carrying a latch for normally restraining said releasable member, said bimetal trip element being operable in response to predetermined current conditions in the circuit of its pole to flex without pivoting and effect release of the releasable member of its pole, the contact arms and actuating means of the several poles being disposed side by side, manually operable means for moving said overcenter springs to actuate said contact arms, and means comprising an interlock bar disposed to be moved by the opening movement of the contact arm of either pole when tripped to move the bimetal trip element of the other pole about its pivot to effect tripping of the other pole.

10. In a multipole circuit breaker, relatively movable contacts for each pole comprising a stationary contact and a cooperating movable contact carried by a movable contact arm, an actuating means for each contact arm for moving

the contact arm to open and to closed circuit position, each actuating means including a member releasable to cause movement of the contact arm to open circuit position and a pivoted current-responsive bimetal trip element carrying a latch for normally restraining the releasable member, said bimetal trip element being operable in response to predetermined current conditions in the circuit of its pole to flex without pivoting and effect release of the releasable member of its pole, the contact means and actuating means of the several poles being disposed side by side, and means comprising a transversely disposed bar pivoted intermediate its ends about an axis parallel to the plane of movement of the contact arms and movable by the opening movement of the contact arm of either pole when tripped to move the bimetal trip element of the other pole about its pivot to effect tripping of the other pole.

11. A multipole circuit breaker comprising a set of separable contacts and a movable contact arm therefor for each pole, an actuating means for each contact arm for moving the contact arm to open and to closed circuit position, the actuating means of each of a plurality of the poles including a member releasable to cause movement of the contact arm to open circuit position and a pivoted current-responsive bimetal trip element carrying a latch for normally restraining the actuating member and having an arm held in engagement with an adjusting element by a spring, said bimetal trip element being operable in response to predetermined current conditions in the circuit of its pole to flex without pivoting and effect release of the releasable member of its pole, the contact means and actuating means of the several poles being disposed side by side, and means comprising a transversely disposed interlock bar movable by the opening movement of the contact arm of any pole when tripped to move the bimetal trip element of other of the poles about its pivot to effect tripping of the other pole, said interlock bar being pivoted intermediate its ends about an axis parallel to the plane of movement of the contact arms and engageable with the arms of said bimetal trip elements on the side opposite the springs.

12. A multipole circuit breaker comprising a movable contact arm for each pole, an actuating means for each contact arm for moving the contact arm to open circuit position, each actuating means including a spring biased member mounted for movement independently of and relative to said contact arm and releasable to cause automatic operation of the contact arm to open circuit position, a spring for actuating said releasable member and said contact arm, a latch for normally restraining the releasable member, and a current-responsive trip element operable in response to predetermined current conditions in the circuit of its pole to operate the latch and effect release of the releasable member of its pole, means operable by the kinetic energy of either contact arm at the end of its opening movement following tripping thereof for operating the latch of the other pole to disengage the releasable member of said other pole and thereby effect tripping of said other pole.

MERRILL G. LEONARD.
